R. H. SPRINGSTEED, OF VANDALIA, MICHIGAN.

Letters Patent No. 92,119, dated June 29, 1869.

IMPROVED STOVE-PIPE SHELF.

The Schedule referred to in these Letters Patent and making part of the same.

To whom it may concern:

Be it known that I, R. H. SPRINGSTEED, of Vandalia, in the county of Cass, and State of Michigan, have invented a new and useful Improvement in Stove-Pipe Shelf; and I do declare that the following is a true and accurate description thereof, reference being had to the accompanying drawings, and to the letters of reference marked thereon, and being a part of this specification.

The drawings represent my invention in two different positions—

Figure 1 being a plan view of the top with the sections separated, and

Figure 2 being a similar view, with the sections together, clasping a section of stove-pipe.

Like letters indicate like parts in each figure.

The nature of my invention relates to an improved construction of a shelf designed to be secured around a stove-pipe, for the purpose of keeping such articles as may be placed upon said shelf warm, without the danger of burning, as is frequently the case when the articles are placed upon the top, or in the oven of the stove.

The invention consists in a grated shelf for the purpose, made in two equal sections, and provided with a corrugated collar, and such fastenings as will hold the same firmly together and in position, and, at the same time, allow the shelf to be fitted to a variety of sizes of stove-pipe.

A A, in the drawings, represent the two sections of a stove-shelf, the inner rims of which are corrugated, as shown at a a, for the purpose of indenting the stove-pipe, and thereby grasping it more firmly.

Each one of these sections is provided with a slotted ear, b b, and a corresponding curved brace, c c,

which passes through and interlocks with the slotted ear, in such a manner that the outer end of each of the braces c c passes under and sustains the edge of the opposite section.

Secured to each section is also a toothed bar, B, the teeth of which are upon the under side thereof, and not shown in the drawings.

The top of the opposite bar of the sections is chamfered off, as at e e, to present a sharpened edge to engage with the toothed bars.

O represents a horizontal section of a stove-pipe.

The stove-pipe being in a vertical position, fits the sections around it, interlocking the brace c and slotted ear b, and engaging the toothed bar with the sharpened edge e, upon one side of the pipe. These interlock the brace and slotted ear upon the other side of the pipe, and press the two sections together until the corrugations a a indent the pipe slightly, and then engage the toothed bar and sharpened edge upon the same side together, and the shelf will be firmly secured to the pipe, and ready for use.

Its adaptations to various sizes of pipe will readily be seen, by means of the toothed bars.

What I claim as my invention, and desire to secure by Letters Patent, is—

The combination of the corrugated stove-pipe collar, the toothed bars B, and the sharpened edges e e, with the slotted ears b b, and curved braces c c, in connection with the sectional shelf A A, as and for the purpose before mentioned.

R. H. SPRINGSTEED.
